R. D. BURCHILL,
MOTOR SLEIGH.
APPLICATION FILED MAR. 20, 1916.

1,210,899.

Patented Jan. 2, 1917.

UNITED STATES PATENT OFFICE.

RICHARD D. BURCHILL, OF TAMPA, FLORIDA.

MOTOR-SLEIGH.

1,210,899.

Specification of Letters Patent. Patented Jan. 2, 1917.

Application filed March 20, 1913. Serial No. 35,433.

To all whom it may concern:

Be it known that I, RICHARD D. BURCHILL, a citizen of the United States, residing at Tampa, in the county of Hillsborough and State of Florida, have invented a new and useful Motor-Sleigh, of which the following is a specification.

The device forming the subject matter of this application is a motor sleigh, and one object of the invention is to provide novel actuating members, which, coacting with the ice-covered or snow-covered ground, impart movement to the sleigh.

A further object of the invention is to provide novel means for driving the actuating members.

The invention contemplates novel means whereby the actuating members may be coupled up operatively with an engine.

It is within the province of the disclosure to improve generally and to enhance the utility of devices of that type to which the present invention appertains.

With the above and other objects in view which will appear as the description proceeds, the invention resides in the combination and arrangement of parts, and in the details of construction hereinafter described and claimed, it being understood that changes in the precise embodiment of the invention herein disclosed can be made within the scope of what is claimed without departing from the spirit of the invention.

In the accompanying drawings:—Figure 1 shows the invention in vertical longitudinal section, parts appearing in elevation; and Fig. 2 is a top plan, wherein divers parts are broken away.

In carrying out the present invention there is provided a supporting structure including a platform 1 carrying one or more seats 2 and including a boot 3.

The invention includes a rear sled 4 united with the platform 1 by knees, one of which is widened for reinforcement, as shown at 5. Supported on the knees 5 are pivot elements 6 on which brakes 7 are mounted to swing, the upstanding ends of the brakes being denoted by the numeral 8. The broadened knees 5 carry pivot elements 6^a, constituting fulcrum for levers 10 of the first order, the rear ends of the levers being adapted to coact with the ends 8 of the brakes 7. The forward ends of the levers 10 are united by a rod 11. Pivoted assembly with the rod 11 intermediate its ends is a rigid connec-

tion 12 pivoted to the lower end of a lever 14 fulcrumed intermediate its ends on the platform 1.

When the lever 14 is swung in the direction of the arrow A into the position shown in Fig. 1, the connection 12 is advanced, tilting the levers 10 upon their fulcrum 6^a, the rear ends of the levers coacting with the upper ends 8 of the brakes 7 and swinging the brakes into the position shown in Fig. 1, wherein the lower ends of the brakes project below the runner of the sled 4. When the lever 14 is swung in a direction opposite to that indicated by the arrow A, the rear ends of the levers 10 are moved out of engagement with the upper ends 8 of the brakes 7, and when the sleigh is advanced, the upper ends 8 of the brakes 7 will swing forwardly, due to the engagement between the lower end of the brakes and the ground, the hold of the lower ends of the brakes on the ground thus being broken.

The numeral 15 designates a turn table located below the platform 1 at the front end thereof. Projecting downwardly from the platform 1 is a bearing 16, balls 17 being interposed between the bearing 16 and the turn table 15. A king bolt 18 is mounted in the platform 1 and passes downwardly through the bearing 16 and through the turn table 15, the construction being such that the turn table 15 may rotate in a substantially horizontal plane on the king bolt.

The numeral 19 designates a front sled including top rails 20 having bearings 21 receiving trunnions 22 projecting from the lateral edges of the turn table 15. The front sled 19 is so connected with the turn table 15 that when the turn table 15 is rotated on the king bolt 18, to effect a steering of the structure, the front sled will participate in the movement. Owing to the fact that the front sled 19 is connected with the turn table 15 by means of the trunnions 22 and the bearings 21, the sled is permitted to have a vertical swinging movement, so that the sled will coöperate with uneven surfaces and move readily into and out of pitch-holes. Fixed to and upstanding from the turn table 15 is a post 23.

The numeral 24 designates a link. A bearing 25 is mounted on the platform 1. Journaled for rotation in the bearing 25 is a steering shaft 26 having a wheel 27 accessible to a person occupying the seat 2. The steering shaft 26 is provided at its

lower end with a crank arm 28. Ball and socket joints 29 connect one end of the link 24 with the post 23, and connect the other end of the link 24 with the crank arm 28.

5 When the shaft 26 is rotated by means of the wheel 27, the crank arm 28 through the instrumentality of the link 24 and the post 23 will cause the turn table 15 to rotate on the king bolt 18, the front sled 19, accordingly, being deflected to one side or the other, and thus a steering of the structure may be brought about.

10 Fixed to and depending from the turn table 15 adjacent the forward end thereof are bearings 30 in which is journaled for rotation a shaft 31 having cranks 34. Fixed to and depending from the turntable 15 adjacent the rear end thereof are bearings 32 in which is journaled for rotation a shaft 33 having cranks 35. A sprocket wheel 36 is secured to the shaft 33, and a sprocket wheel 37 is secured to the shaft 31.

15 The numeral 38 denotes the casing of a suitable transmission mechanism of any sort, fixed to the turntable 15, the platform 1 having an arcuate opening 39 in which the transmission mechanism moves when the turntable 15 is rotated, during the steering operation.

20 The numeral 40 designates a shaft constituting a part of the transmission mechanism and located below the turntable 15. Mounted on the shaft 40 are sprocket wheels 41. Chains 42 connect the sprocket wheels 41, respectively, with the sprocket wheels 36 and 37 of the shafts 33 and 31. At 43 there appears the shaft of an internal combustion engine 44, the shaft 43 being operatively connected with the transmission mechanism, 25 and the engine 44 being mounted on the turntable 15. The platform 1 is provided with an arcuate opening 45 through which the engine 44 projects, the construction being such that when the turntable 15 is moved 30 during the steering operation, the engine 44 which is fixed to the turntable, may move with respect to the platform 1.

25 A plurality of ground-engaging means are provided, whereby movement may be imparted to the sleigh. But one of these ground-engaging mechanisms need be described, although four of them are provided, the ground engaging mechanisms being operatively connected with the cranks 34 35 and 35 of the shafts 31 and 33. The description will be confined to one of the cranks 35.

30 Operatively connected with the crank 35 is a casing 46 within which is located a plunger 47, the forward end of the casing 46 being recessed as shown at 48 to receive the forward end of the plunger. Surrounding a portion of the plunger 47 and located in the casing 46 is a spring 49 the forward 35 end of which abuts against the forward end

of the casing, the rear end of which is engaged with an abutment on the plunger 47, the abutment being in the form of a cross pin 50 if desired. The rear, lower end of the plunger 47 is pivoted as shown at 51 to an arcuate shoe 52 provided with depending teeth 53, the rear end of the shoe 52 being pivoted as shown at 54 to a link 55 pivoted as indicated at 56 to the turntable 15. The turntable 15 is provided with openings 57 in which the cranks 34 and 35 and the casings 46 move when the shafts 31 and 33 are rotated.

35 In practical operation, when the engine 44 is in operation, the shaft 43 is rotated and motion is imparted through the transmission mechanism 38 to the shaft 40. The sprocket wheels 41 are rotated and by means of the chains 42 and the sprocket wheels 36 and 37, rotation is imparted to the shafts 33 and 31, the cranks 35 and 34 of which are thus operated. A reciprocating swinging movement is imparted to the plungers 47 by way of the casings 46, the springs 49 serving to take up excessive jars. The shoes 52 are worked to and fro, the links 55 swinging on the pivot elements 56. Noting the showing of the forward and rear shoes 52 in Fig. 1 of the drawings, it will be obvious that the shoes are lifted as they are moved forwardly, and that the shoes descend as they move rearwardly. The construction, therefore, is such that the sleigh under the impulse of the shoes 52 will be given a forward movement, the teeth 53 giving the shoes a hold on the ice covered ground, as the shoes 52 move rearwardly.

40 The engine 44, the transmission mechanism 38 and attendant parts may be housed beneath a suitable hood 58 mounted on the forward end of the platform 1.

Having thus described the invention, what is claimed is:

1. In a motor sleigh, a platform; a rear sled connected with the platform; a turntable journaled for rotation on a vertical axis and located at the forward end of the platform; a forward sled assembled with the turntable; means for rotating the turntable about a vertical axis; a ground-engaging driving means carried by the turntable; an engine mounted on the turntable; and means for operatively connecting the engine with the driving means.

2. In a motor sleigh, a platform; a rear sled assembled with the platform; a turntable mounted on the platform adjacent the forward end of the platform for rotary movement about a vertical axis; means for rotating the turntable about a vertical axis; a front sled pivotally assembled with the turntable for swinging movement in a vertical plane; an engine on the turntable; a ground-engaging driving means carried by the turntable; and mechanism for opera-

tively connecting the engine with the driving means.

3. In a motor sleigh, a platform; a rear sled assembled with the platform; a turntable mounted to rotate about a vertical axis and located adjacent the forward end of the platform; means for rotating the turntable; forward and rear shoes located below the platform; links connecting the rear ends of the shoes with the turntable; shafts journaled on the turntable and having cranks; connections between the cranks and forward ends of the shoes; an engine mounted on the turntable; and means for operatively connecting the engine with the shafts.

4. In a motor sleigh, a platform; a rear sled carried by the platform; a turntable journaled for rotation on the platform for movement on a vertical axis; means for rotating the turntable about a vertical axis; a front sled carried by the turntable; a shoe located below the platform a link connecting the rear end of the shoe with the turntable; a shaft journaled on the turntable and provided with a crank; a connection between the crank and the forward end of the shoe, the connection including a cushioning spring; an engine mounted on the turntable; and means for operatively connecting the engine with the shaft.

5. In a device of the class described, a sled; a table connected with the sled; front and rear ground-engaging shoes located below the table; links connecting the rear ends

of the shoes with the table; shafts journaled for rotation on the table and provided with cranks; connections between the cranks and the forward ends of the shoes; a transmission mechanism mounted on the table between the shafts, the transmission mechanism including a third shaft; sprocket wheels on the third shaft and on the crank shafts; sprocket chains connecting the sprocket wheels of the third shaft with the sprocket wheels of the crank shafts; and an engine mounted on the table and connected with the transmission mechanism.

6. In a device of the class described, a sled; a table carried thereby; a ground-engaging shoe disposed below the table; a link connecting the rear end of the shoe with the table; a crank shaft journaled on the table; an engine located on the table and operatively connected with the crank shaft; a plunger pivoted at its lower end to the forward end of the shoe; a casing pivotally connected with the crank shaft and receiving the plunger slidably; and a spring forming an operative connection between the casing and the plunger.

In testimony that I claim the foregoing as my own I have hereto affixed my signature in the presence of two witnesses.

RICHARD D. BURCHILL.
